PREDETERMINING COUNTER WITH RESETTING CONTROLLED SWITCH CLOSING MEANS

James B. Hoye, Hartford, Conn., assignor to
Veeder-Root Incorporated, Hartford, Conn., a
corporation of Connecticut

Application June 27, 1950, Serial No. 170,504

5 Claims. (Cl. 235—132)

1

The present invention relates to counters and more particularly to an improvement in the switch control members of a high speed predetermining counter of the type disclosed in the Harvey N. Bliss Patent No. 2,159,314, granted May 23, 1939.

In counter mechanisms of the type to which the present invention is directed, the arrangement is such that the counter may be attached to an associated mechanism such as a loom or the like and can be set to halt the output of the associated mechanism upon the completion of a predetermined number of counting operations. Thereafter the counting mechanism can be reset and the resetting automatically conditions the associated apparatus for repeating the said predetermined number of counting operations.

It is an aim of the present invention to provide an improved counter of the type referred to in which the resetting operation is improved so that it is ensured that the counter will be accurately reset to zero without error and to further ensure that the repeat operation of the associated apparatus will not be initiated until the resetting of the counter is fully completed.

A further aim of the invention is to provide a device of the character described wherein the mechanism for closing an associated control switch will not be operated until the very completion of the resetting operation and yet this will not cause a heavy non-uniform load or strain to be placed on the resetting mechanism rendering the latter difficult to operate and susceptible to breakage.

A further object of the invention is to accomplish the above aims by the use of simple mechanism which is easy to fabricate and assemble and which will operate over long periods of time without failure and without error.

Other objects will be in part obvious, and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawings:

Fig. 1 is a front view of a high speed counter of the predetermining type embodying the present invention, the predetermining number wheels being shown in the zero position and the casing being broken away to show the interior of the device.

Fig. 2 is a plan view of the counter shown in Fig. 1 with the cover removed.

2

Fig. 3 is an end cross-sectional view taken along the line 3—3 of Fig. 1.

Fig. 4 is a cross-sectional view taken along the line 4—4 of Fig. 1; and

Fig. 5 is a cross-sectional view taken along the line 5—5 of Fig. 1, the predetermining number wheels being in other than zero position.

As mentioned above, the present invention is an improvement upon a high speed counter of the predetermining type as shown in the Bliss patent, supra, and reference may be had to this patent for any additional details of construction, some of which are omitted from the present description in the interests of simplicity and brevity of presentation and which are not essential to an understanding of the present invention.

Referring to the drawings, the counter mechanism of the present invention is mounted in a housing 10 of generally rectangular cross section and having side plates 11 and 12. Journaled in the side plates 11 and 12 and extending across the counter is a reset shaft 13 provided at one outer end with a crank 14 by means of which the reset shaft may be manually rotated.

Mounted on the reset shaft 13 are a plurality of counter wheel assemblies 15, each consisting of a number wheel 16 and an adjustable predetermining wheel 17. The counter wheel assemblies 15 are constructed as shown in the Harvey L. Spaunburg Patent No. 2,040,026 granted May 5, 1936, to which reference may be had for details of construction. Normally, the number wheels 16 and adjustable predetermining number wheels 17 are connected together for simultaneous rotation. However, the angular position of the adjustable predetermining number wheels 17 relative to their respective number wheels 16 may be adjusted. This is accomplished by moving the adjustable predetermining number wheel 17 axially relative to the number wheel 16 and then rotating it to the selected position, whereupon the adjustable wheel 17 may be released to return again into non-rotatable engagement relative to the number wheel 16.

The counter wheel assembly 15 of the first or lowest order which, in the specific embodiment shown in the drawings, is located at the right-hand end of the counter as viewed in Figs. 1 and 2, is driven in a continuous manner as distinguished from a step-by-step actuation through reducing gearing operated by the counter drive shaft 18. The counter drive shaft 18 is to be connected to an associated mechanism with which the counter is to be utilized, the connecting means and associated apparatus being no part

of the counter mechanism.

of the present invention and being omitted from the drawings. The counter drive shaft 18 extends generally parallel to the reset shaft 13 and is similarly journaled in the end plates 11 and 12 of the housing 10. At the end of the shaft 18 adjacent the side plate 12 there is fixed a pinion 19 which is in mesh with a large gear 20 freely mounted on the reset shaft 13. Fixed to the large gear 20 is a pinion 21 which is in mesh with a large gear 22 loosely mounted on the shaft 18. Fixed to the large gear 22 is a pinion 23 which is in mesh with a large gear 24 which is coupled to the driven gear 25 of the first counter wheel assembly 15, the driven gear 25 being fixed to the part of the number wheel 16 of the counter wheel assembly.

The remaining counter wheel assemblies 15 of higher order are driven from the first counter wheel assembly of lower order through usual transfer mechanism including mutilated pinions 26 mounted on an auxiliary shaft 27 and each meshing with the two-tooth driving gear 28 of the preceding counter wheel assembly 15 of lower order and also with the driven gear 25 of the succeeding counter wheel assembly 15 of higher order. The usual notched locking disc 29 is provided adjacent each two-tooth driving gear 28 to prevent turning of the gears except during a transfer operation. By the mechanism thus briefly described, the initial or first counter wheel assembly 15 of lowest order is driven directly by the counter drive shaft 18 at a reduced rate of speed and the count registered by this counter wheel assembly is transferred stepwise to the counter wheel assembly 15 of higher order, each turn of a counter wheel assembly 15 of lower order being utilized to turn the succeeding counter wheel assembly one-tenth turn.

The counter wheel assemblies 15 are provided with the usual reset pawls (not shown) by means of which the counting mechanisms can be picked up and returned to a zero position by rotation of the reset shaft 13, the reset shaft 13 being provided with a longitudinal resetting groove 30 for engaging the pawls. The outer end of the reset shaft 13 opposite from the crank 14 is provided with a pin 31 which is adapted to engage against a lug 32 formed on a disc 33 which is secured to the side plate 11. The lug 32 is provided with an inclined cam surface 34 on the side engaged by the pin 31 when the reset shaft 13 is turned in a resetting direction, i. e. clockwise as viewed in Fig. 3 of the drawings. In order to perform a resetting operation, the operator must thrust the reset shaft 13 against the action of spring 35 in order to permit the pin to clear the lug 32. By reason of the inclined cam surface 34 on the lug 32, it is ensured that the reset shaft will be turned backwards, i. e. counter-clockwise as viewed in Fig. 3, through a small angle of rotation before the resetting operation can be carried out. This slight backward rotation of the reset shaft ensures that all of the counter wheel assemblies will be picked up and returned to initial starting position. The return of the counting mechanisms to initial starting position is indicated by the abutment of the pin 31 against the lug 32 and this effectively halts the resetting operation unless the operator again thrusts the reset shaft inwardly to again clear the lug 32. A so-called "no-back" pawl 39 is pivoted on shaft 27 for engagement with notch 42 in cam 75 (to be described later) which is secured to the reset

shaft 13 to prevent reverse turning of the reset shaft past the lug 32.

Attached to the top of the housing 10 and pivoted at 36 is a cover 37 provided with a window 38 through which the readings on the counter wheel assemblies 15 can be viewed. The cover 37 can be readily pivoted to open position to permit the operator to change the position of the adjustable predetermining counter wheels 17 relative to the respective number wheels 16.

Fastened to the back of the housing 10 is an electric switch 40 having an actuating member 41 extending through an aperture in the rear wall of the housing 10. The switch 40 may be of any desired construction and in the specific embodiment the switch is operated by moving the actuating member 41 axially. The actuating member 41 is biased outwardly of the switch, i. e. toward the counter, which is the position of the switch when the contacts are closed. Conversely, when the actuating member 41 is pressed inwardly of the switch, i. e. away from the counter, the switch contacts are open.

As explained in the prior Bliss Patent No. 2,159,314, referred to above, the function of the counter is to close the switch 40 at the end of a resetting operation and to reopen the switch 40 when a predetermined number of counting operations has been completed. When the counter wheel assemblies 15 have been reset to initial starting position, as discussed above, the number wheels 16 will register zero, while the adjustable predetermining number wheels 17 will register the number of counting operations to be performed. The indicia on the number wheels 16 and adjustable predetermining number wheels 17 run in the reverse order to each other so that the number of counting operations performed will be progressively indicated on the number wheels 16 and will be subtracted from the reading on the adjustable predetermining wheels 17, with the final result that the predetermined number of counting operations will be shown eventually on the number wheels 16 at which time the adjustable predetermining number wheels 17 will register zero.

Freely mounted on a shaft 50 extending between the side plates 11 and 12 is a sleeve 51, having fixed thereto at one end an operating arm 52, whose free end 53 is adapted to engage against the end of the switch actuating member 41. The free end 53 is curved to act as a cam so that, when the arm 52 is in the position shown in Fig. 3 of the drawings, the switch 40 is held in open position, but when the arm 52 is moved counter-clockwise, as viewed in Fig. 3 to the position shown in Fig. 5, it will permit the switch actuating member 41 to move outwardly sufficiently to close the switch 40.

The operating arm 52 has fixed thereto a pin 55 to which is connected one end of a coil spring 56 which extends around the shaft 50 and has its opposite end connected to a screw 57 fixed to the shaft 50. As a result, the operating arm 52 is biased by the coil spring 56 in a direction for closing the switch 40.

Pinned to the shaft 50 in side-by-side relationship with the arm 52 there is provided a control arm 60 having an elongated notch 61 in which is received the pin 55 previously referred to as being fixed to the arm 52. The notch 61 and pin 55 provide a lost motion connection between the shaft 50 and operating arm 52.

The end of the shaft 50 adjacent the side plate 11 has fixed thereto a bell crank 63 which

is urged in a clockwise direction as viewed in Fig. 3 by a coil spring 64 extending around the shaft 50, having one end engaging the bell crank 63 and having the other end received in a notch 65 provided in a pin 66 extending from the rear wall of the housing 10.

The bell crank 63 is adapted to be latched in the rotated position shown in Fig. 5 of the drawings by a latch 67 which is pivotally mounted on a shaft 68. Also pivoted on the shaft 68 is a frame 69 carrying a roller bar 70 which is adapted to engage the peripheries of the predetermining number wheels 17. The frame 69 is biased in a counterclockwise direction as viewed in Fig. 5 by the spring 71 attached at one end to the frame and at the other end to the rear of the housing 10.

The peripheries of each of the predetermining number wheels 17 are provided with a notch 17a which will receive the roller bar 70 when the predetermining number wheels 17 register zero when viewed through the window 38. At all other times the notches 17a are not in alignment, thereby causing the roller bar 70 to ride up on the peripheries of the predetermining number wheels 17.

The frame 69 is connected to the latch 67 by means of a pin 72 on the frame 69 which extends into an elongated slot 73 in the latch. The result of this lost motion connection between the frame 69 and the latch 67 is that the roller bar 70, and hence the frame 69, may be cammed outwardly by the peripheries of the predetermining number wheels 17 without changing the position of the latch 67, but when the roller bar 70 is received in the aligned notches 17a, the latch 67 will be positively driven to unlatching position. A spring 74 extending between the latch 67 and the roller bar 70 urges the latch 67 into latching position.

As previously mentioned, the number of counting operations to be performed is registered on the adjustable predetermining number wheels 17, and when the reading on these number wheels 17 is zero, the notches 17a are aligned, permitting the roller bar 70 to be received therein. Spring 71 causes the roller bar 70 to enter the aligned notches 17a and the resulting motion of the frame 69 drives the latch 67 through the pin 72 and slot 73 connection previously described to unlatch the bell crank 63, permitting the latter to turn under the influence of spring 64, thus turning the shaft 50. The rotation of shaft 50 causes one end of the notch 61 to engage the pin 55 on the operating arm 52, thus moving the operating arm 52 to the open switch position, thus halting the operation of the associated mechanism.

When the counter is reset, as by turning the reset shaft 13 by means of the crank 14, as previously described, the roller bar 70 is first cammed out of the notches 17a. By reason of a lost motion connection between the roller bar frame 69 and the latch 67, there is no movement of the latch 67 required although the latch operating spring 74 is tensioned, thus urging the latch 67 into latching position. Fixed to the adjacent end of the resetting shaft 13, there is provided a cam 75 which engages the bell crank 63 and cams the latter to latching position during the rotation of the reset shaft. As soon as the bell crank 63 is cammed to latching position, the latch 67 is immediately engaged therewith under the influence of spring 74.

The movement of the bell crank 63 to latching

position, as previously mentioned, pivots the control arm 60 sufficiently to permit the operating arm 52 to move to switch "On" position under the influence of spring 56. However, movement of the operating arm 52 is prevented by means of an arm 76 fastened to the opposite end of the sleeve 51 and engaging against the periphery of a notched disc 77 fixed to the reset shaft 13. The notch 78 of the notched disc 77 is so positioned that it will receive the end of the arm 76 just at the very end of the resetting operation, which ensures that the switch 40 will not be closed until resetting has been completed.

As will be apparent, the reception of the end of arm 76 in the notch 78 of disc 77 closes the switch 40, thus setting the associated apparatus in operation for the repetition of the predetermined number of counting operations, and the operation of the associated mechanism will continue until notches 17a of the predetermining number wheels 17 are again aligned, thereby repeating the cycle just described.

It thus will be seen that there has been provided, in accordance with the invention, an improved switch operating mechanism whereby the switch is not actuated until at the very end of the completion of a resetting operation and at the very end of a counting operation. At the same time the bell crank 63 may be latched into operative position at any time during the resetting operation, thus making it unnecessary to design the cam 75 with close tolerances or so as to place excessive strain on the resetting mechanism or making the resetting mechanism hard to operate.

As many changes could be made in the above construction and many apparently widely different embodiments of this invention could be made without departing from the scope thereof, it is intended that all matter contained in the above description shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In a counter comprising a reset shaft, a plurality of number wheels on the shaft, means for driving the number wheels, and means effective when the reset shaft is turned for returning the number wheels to initial starting position, the combination therewith of means for operating an associated mechanism including a movably mounted actuating arm, means biasing the arm into a first position, means including a cam on the reset shaft for preventing movement of the actuating arm to said first position except when the reset shaft is turned to full reset position, a control member for the actuating means, means forming a lost motion connection between the control member and the actuating means whereby movement of the control member to a first position will move the actuating member to a second position and movement of the control member to a second position will permit the actuating member to move to said first position, means biasing the control member into said first position, means for latching the control member in said second position, means including predetermining means on the number wheels for un-

latching the latching means following completion of a predetermined count, and means operated by the reset shaft for moving the control member to latching position during a resetting operation.

2. In a counter comprising a reset shaft, a plurality of number wheels on the shaft, means for driving the number wheels, and means effective when the reset shaft is turned for returning the number wheels to initial starting position, the combination therewith of a switch actuating member, means biasing the member into switch closed position, means including a cam on the reset shaft for preventing movement of the switch actuating member to switch closed position except when the reset shaft is turned to full reset position, a control member for the switch actuating member, means forming a lost motion connection between the control member and the actuating member whereby movement of the control member to a first position will move the actuating member to switch open position and movement of the control member to a second position will permit the actuating member to move to switch closed position, means biasing the control member into said first position, means for latching the control member in said second position, means including predetermining means on the number wheels for unlatching the latching means following completion of a predetermined count, and means operated by the reset shaft for moving the control member to latching position during a resetting operation.

3. In a counter comprising a reset shaft, a plurality of number wheels on the shaft, means for driving the number wheels, and means effective when the reset shaft is turned for returning the number wheels to initial starting position, the combination therewith of a switch actuating member, means biasing the member into switch closed position, means comprising a cam on the reset shaft and a cam follower secured to the actuating member for preventing movement of the member to switch closed position except when the reset shaft is turned to full reset position, a control member for the switch actuating member, means comprising a slot in one of the said members and a pin on the other of said members received in the slot forming a lost motion connection between the control member and the actuating member whereby movement of the control member to a first position will move the actuating member to switch open position and movement of the control member to a second position will permit the actuating member to move to switch closed position, means biasing the control member into said first position, a latch member normally holding the control member in said second position, means including predetermining means on the number wheels for tripping the latch member following completion of a predetermined count, and means including a cam on the reset shaft for moving the control member to latching position during a resetting operation.

4. In a counter comprising a reset shaft, a plurality of number wheels on the shaft, means for driving the number wheels, and means effective when the reset shaft is turned for returning the number wheels to the initial starting position, the combination therewith of a switch

actuating member, means biasing the member into switch closed position, means comprising a notched disc on the reset shaft and an arm attached to the actuating member for engaging the periphery of the disc, said disc and arm being constructed and arranged so that the actuating member is held in switch open position by engagement of the arm with the periphery of the disc except when the arm is received in the notch at the completion of a resetting operation, control means including a control member and means forming a lost motion connection between the control member and the actuating member whereby movement of the control member to a first position will move the actuating member to switch open position and movement of the control member to a second position will permit the actuating member to move to switch closed position, means biasing the control member into said first position, a latch member normally holding said control means against movement of the control member into said first position, means including predetermining means on the number wheels for unlatching the latch upon completion of a predetermined count, and means including a cam on the reset shaft for moving the control member to latching position during a resetting operation.

5. In a predetermining counter comprising a reset shaft, a plurality of operatively connected predetermining number wheels each having a notch in its periphery mounted on the reset shaft, a roller bar having rollers engaging the peripheries of said wheels and adapted to be received by said notches when the latter are in alignment, and means effective when the reset shaft is turned for returning the number wheels to an initial starting position, the combination therewith of a switch actuating member, means biasing the member into switch closed position, means including a cam on the reset shaft for preventing movement of the switch actuating member to switch closed position except when the reset shaft is turned to full reset position, a control member for the switch actuating member, means forming a lost motion connection between the control member and the actuating member whereby movement of the control member to a first position will move the actuating member to switch open position and movement of the control member to a second position will permit the actuating member to move to switch closed position, means biasing the control member into said first position, means including a latch for holding the control member in said second position, means operated by said roller bar for tripping the latch when the rollers are received in the notches of said wheels, and means including a cam on the reset shaft for moving the control member to latching position during a resetting operation.
